CLAIM

The ornamental design for a denture cleaner or the like,
as shown.

DESCRIPTION

FIG. 1 is a front perspective view of a denture cleaner
or the like showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a right-side elevational view thereof; and

FIG. 7 is a left-side elevational view thereof.
